UNITED STATES PATENT OFFICE.

B. FRANK TEAL, OF PHILADELPHIA, PENNSYLVANIA.

GRAIN-CAR DOOR.

SPECIFICATION forming part of Letters Patent No. 280,688, dated July 3, 1883.

Application filed May 11, 1882. (No model.)

To all whom it may concern:

Be it known that I, B. FRANK TEAL, a citizen of the United States, and a resident of Philadelphia, county of Philadelphia, and State of Pennsylvania, have invented certain new and useful Improvements in Grain-Car Doors, of which the following is a specification.

My invention relates to that class of cars intended for carrying grain; and it consists in 10 constructing the grain-doors, as fully described hereinafter, to secure the ready removal of the grain when the same is banked against the door.

It further consists in a ready means of 15 moving, stowing, and replacing the door-panels without disconnecting them from the car.

It is necessary in employing grain-cars to quickly remove the grain-doors, that the grain may flow by gravity from the cars. As the men 20 employed in removing the grain are paid in proportion to the amount of grain transferred, no trouble is taken to remove any obstruction that interteres with the detaching of the doors, or to remove the portion of grain the 25 pressure of which jams the panels immovably against their bearings; but instead the panels are broken or split and cut out with axes, occasioning considerable loss to the car-owners. As it is almost impossible to construct the 30 doors so that they will invariably slide easily in their bearings while sustaining a body of grain behind them, I have constructed the grain-doors with outwardly-opening sections or valves at the lower parts, which may be 35 securely locked, but readily unlocked and swung outward, permitting the body of grain behind the door to flow freely outward, until the panels are free from pressure and can be readily removed. Such valves may be made 40 in different ways. For instance, the lower panel may be cut away, forming a long opening, which is provided with a hinged door swinging outwardly; or the lower panel may be hinged at one end to swing outward, a 45 suitable locking device being used to hold the other end when closed. I prefer, however, to employ the construction shown in the drawings, in which—

Figure 1 is a side part sectional view of sufficient of a grain-car to show my improved door closed. Fig. 2 is a perspective view in

section, the door open. Fig. 3 is a view from the inside, showing the side of the car.

The panels slide between vertical guides *a* 55 at the sides of the door, and may be detachable therefrom or permanently but movably retained, as hereinafter described, and the panel *A'* is hinged by pivots, (shown in dotted lines, Fig. 1,) so that it can be turned outward and down to a horizontal position, Fig. 60 2, a pivoted arm, *b*, which may be swung with its end behind a keeper, *d*, as shown at Fig. 1, serving as a means of locking the panel when in a vertical position. By knocking up the end of the arm the panel is released, and, falling 65 forward under the pressure of the grain, permits the latter to flow outward until there is no grain in contact with the upper panels, which can then be readily removed, suitable shoulders or stops, *t*, preventing the said panels descending below the position shown in Fig. 3. To afford better security, the middle panel, *A'*, may be divided into two sections, *h h'*, Fig. 2, the upper section being slightly 70 longer than the lower, so as to rest with its 75 ends on the stops *t t*, which limit its downward motion, and the lower section being hinged to the upper, so as to swing outward under pressure. The front cleats or guides are cut away at *yy* to permit this forward swinging movement, 80 the hinged section being retained in place by contact with the outer lower panel, *A''*, when the latter is turned upward and locked. By this means the breaking or displacement of the arm *b* will not result in the loss of grain at the 85 outward movement of the lower panel, *A''*, and the latter will be limited by its contact with the outer sliding door, I, when the latter is closed, the section *h'* being held in place until the lower panel falls to a horizontal position. 90

As the panels are usually simple straight pieces of board, train-men are apt to be careless with them, and large numbers are lost or stolen. To prevent this I continue the cleats or guides *a d'* to the top of the car, so that the 95 panels can slide upward, but cannot be removed until opposite to recesses *w* in the strip separating the cleats, each recess being just deep enough to receive one of the panels, which may then be slid laterally between 100 guides *i i'* on opposite sides of the door, one panel being moved to one side and the other

to the opposite side, entirely out of the way, but securely held, so as always to be available for use. Each panel has a lug, *s*, near one end, adapted to a notch, *u*, in a rail, *n*, at the top 5 of the door-opening, the parts being arranged so that after a panel is lifted to its full height and pushed a slight extent to one side the lug will bear on the rail and support the panel, preventing tilting and jamming.

10 I claim—

1. The combination of the panels sliding between guides, one having a section hung to swing outwardly, and a supplemental panel, *A'*, hung to swing outward, and a device for locking said latter panel, substantially as set forth.

15 2. The combination of the car having guides for the panels, the outer guide being cut away at *y y*, and panels, one of which is provided

with a hinged section, *h'*, substantially as set 20 forth.

3. The combination, in a car, of the guides *a a'*, receiving separate panels *A A'*, and recesses *w*, and guides *i i'* on opposite sides of the door, and arranged, substantially as specified, to permit different panels to be carried to different sides of the door.

4. The combination, with the car, of panels, one having a hinged section, and stops upon the car limiting the downward movements of 30 the panels, substantially as set forth.

In testimony whereof I have signed my name to this specification in the presence of two subscribing witnesses.

B. FRANK TEAL.
